HOSIERY PROTECTOR

Filed Dec. 27, 1946

UNITED STATES PATENT OFFICE

2,449,115

HOSIERY PROTECTOR

Flora L. Harriman, Lansing, Mich.

Application December 27, 1946, Serial No. 718,819

4 Claims. (Cl. 36—2)

1

This invention relates to a protective garment adapted to be worn over ladies' hosiery, above and adjacent the shoes for especially protecting the back, lower part of the hosiery from being spotted and stained while walking during inclement weather.

Considerable difficulty is encountered by ladies walking during inclement weather in preventing the backs of the stockings, above and adjacent the shoes from becoming spotted. Said spots are almost impossible to avoid and the stains resulting therefrom are very difficult to remove from the hosiery requiring considerable rubbing and thus subjecting the hosiery to excessive wear so as to materially reduce the usable life thereof. Furthermore, the spots and resulting stains are very unsightly and must ordinarily be worn until such time as the stockings or hosiery can be changed for laundering.

It is a primary object of the present invention to provide protectors of extremely simple construction adapted to be employed in pairs and which may be quickly and easily applied to the ankles and around the upper portion of the shoes for protecting the back part of the hosiery from spots and stains.

Another object of the invention is to provide hosiery protectors which may be formed of plastic or other flexible transparent material and from which the spots or stains can be readily removed by wiping.

Still a further object of the invention is to provide hosiery protectors which may be formed of clear transparent plastics or of a colored transparent plastic to conform to hosiery shades.

Still another object of the invention is to provide hosiery protectors which may be readily folded and carried in a raincoat pocket when not in use and which may be constructed to match hat coverings, frequently carried with the raincoat for protecting the hat from rain.

Various other objects and advantages of the invention will hereinafter become more fully apparent from the following description of the drawing, illustrating a preferred embodiment thereof, and wherein:

Figure 1 is a plan view showing one of the hosiery protectors in an extended position;

Figure 2 is a perspective view showing the hosiery protector applied to the left leg and foot;

Figure 3 is a front elevational view showing the hosiery protector applied to the right leg and foot, and

Figure 4 is a rear elevational view showing the protector applied to the left leg.

2

Referring more specifically to the drawing, the hosiery protector in its entirety is designated generally 5 and is formed from a single piece or sheet of flexible plastic or other flexible, waterproof material, and a binding strip, designated generally 7.

The flexible sheet 6 is preferably transparent, or substantially transparent, and may be either clear or of a color to conform to a shade of ladies' hosiery. The sheet 6 is of angular formation having outer substantially straight edges 8 which form substantially a right angle and inner edges which are bound by the intermediate portion of the binding 7 which is stitched at 9 or otherwise secured thereto. The inner edges of the sheet 6 include substantially straight right angularly disposed portions 10 and outer convexly curved portions 11. The portions 11 merge with the outer ends of the outer edges 8 and the binding tape 7 projects therebeyond to form tie strings or tapes 12.

One of the hosiery protectors 5 is applied to each leg and a description of the application of one of said protectors will suffice for the application of both. The center of the protector is positioned 15 across the back of the lower part of the leg and with the apex 13, formed by the edges 8, aligned with the seam of the hose or stocking 14, which encases the leg. The intermediate portion of the binding 7 is disposed around the ankle adjacent 20 the upper edge of the shoe 15 and may, if desired, overlie said edge. The end portions of the sheet 6 are then crossed over the instep, one above the other, as seen in Figures 2 and 3 and pass downwardly under the instep 16 of the shoe 15, as far 25 as said end portions will extend, and the tapes or ties 12, forming continuations of said end portions, are crossed under the shoe instep 16 and brought around and tied at 17 over the instep of the foot and over the crossed portions of the protector 5, for effectively securing the protector 30 around the ankle and lower portion of the leg. With a pair of the protectors 5 thus applied over the hose or stockings 14, water which normally splashes onto the backs of the lower part of the 35 stockings, as when walking in wet or inclement weather, will only strike the protector or shield portion 6 and may be readily wiped therefrom. When not required, the two protecting shields 5 may be readily removed by untying the ends of the tie strings 12 and said protectors may be 40 folded and placed in a raincoat pocket for convenient storage.

Various modifications and changes are contemplated and may obviously be resorted to, without departing from the spirit and scope of the in-

vention as hereinafter defined by the appended claims.

I claim:

1. In a hose protector, a sheet of flexible, waterproof material having corresponding portions disposed at a right angle to one another, said protector being adapted to be disposed with the intermediate portion thereof positioned against the back of the leg and ankle with the outer edges thereof extending around the leg and converging at the back of the leg and the inner edges thereof disposed around the ankle and adjacent the shoe, the end portions of said protector being crossed one over the other over the instep of the foot and under the instep of the shoe.
2. In a hose protector, a sheet of flexible, waterproof material having corresponding portions disposed at a right angle to one another, said protector being adapted to be disposed with the intermediate portion thereof positioned against the back of the leg and ankle with the outer edges thereof extending around the leg and converging at the back of the leg and the inner edges thereof disposed around the ankle and adjacent the shoe, the end portions of said protector being crossed one over the other over the instep of the foot and under the instep of the shoe, and said end portions having ties extending therefrom and adapted to be passed up and secured together over the instep and over the first mentioned crossed portions of the protector.

3. In a hose protector, a sheet of flexible, waterproof material having corresponding portions disposed at a right angle to one another, said protector being adapted to be disposed with the intermediate portion thereof positioned against the back of the leg and ankle with the outer edges thereof extending around the leg and converging at the back of the leg and the inner edges thereof disposed around the ankle and adjacent the shoe, the end portions of said protector being crossed one over the other over the instep of the foot and under the instep of

the shoe, said inner edges being provided with a binding strip extending from end to end thereof and having free end portions forming ties adapted to be extended from the ends of the protector and secured together over the instep, for detachably securing the protector on the leg.

4. A protector shield for hosiery comprising a relatively thin flexible sheet of substantially waterproof material, said sheet having outer substantially straight edges disposed substantially at a right angle and inner edges having substantially right angularly disposed inner portions and outer convex portions converging and merging with the outer ends of said outer edges, a binding tape secured to said inner edges from end to end thereof and having portions projecting from the ends of said inner edges and forming tie strings, said sheet being adapted to be disposed around the ankle and lower portion of the leg with said first mentioned outer edges converging at the back of the leg, the bound edges of the sheet being adapted to be disposed around or adjacent the upper edge of the shoe, the end portions of the protector being crossed one over the other at and over the instep of the foot and extending downwardly under the instep of the shoe, and the end portions of the protector or the tie strings being crossed under the shoe instep and being extended over the instep of the foot and secured together over the first mentioned crossed portions of the protector for securing the protector on the leg and around a portion of the shoe.
